UNITED STATES PATENT OFFICE.

IRA M. CLARKE, OF PITTSBURGH, PENNSYLVANIA, ASSIGNOR TO THE JOHN B. HIGBEE GLASS COMPANY, OF BRIDGEVILLE, PENNSYLVANIA, A CORPORATION OF PENNSYLVANIA.

DESIGN FOR A COMBINED MATCH-BOX HOLDER AND ASH-TRAY.

52,840.

Specification for Design.

Patented Jan. 7, 1919.

Application filed August 12, 1918. Serial No. 249,588. Term of patent 3½ years.

To all whom it may concern:

Be it known that I, IRA M. CLARKE, a citizen of the United States, and resident of Pittsburgh, in the county of Allegheny and State of Pennsylvania, have invented a certain new, original, and ornamental Design for a Combined Match-Box Holder and Ash-Tray, of which the following is a specification, reference being had to the accompanying drawing, forming part thereof, in which—

match box holder and ash tray showing my new design;

Fig. 2 is a section of the same; and

Fig. 3 is a bottom view of the same.

I claim:—

The ornamental design for a combined match box holder and ash tray as shown.

IRA M. CLARKE.
